Patented Dec. 12, 1972

225,452

TRASH RECEPTACLE HOPPER

Floyd R. Gladwin, 21000 E. River Road,
Grosse Ille, Mich. 48138

Filed Apr. 15, 1971, Ser. No. 134,525

Term of patent 14 years

Int. Cl. D7—05

U.S. Cl. D49—35

FIG. 2

FIG. 1

FIG. 1 is a top perspective view of a trash receptacle hopper showing my new design;

FIG. 2 is a bottom perspective view;

FIG. 3 is a top plan view;

FIG. 4 is a side elevational view, the opposite side being a mirror image of the side shown;

FIG. 5 is a cross-sectional view taken on the line 5—5 of FIG. 3;

FIG. 6 is a cross-sectional view taken on the line 6—6 of FIG. 3;

FIG. 7 is a cross-sectional view taken on the line 7—7 of FIG. 3; and

FIG. 8 is a bottom plan view.

I claim:

The ornamental design for a trash receptacle hopper, as shown and described.
